United States Patent

Des. 242,581
Patented Nov. 30, 1976

242,581

MOBILE SIGN

Albert P. Morris, Jr., Rte. No. 16, Abner Cruze Road,
Knoxville, Tenn. 37920

Filed Dec. 5, 1974, Ser. No. 529,691

Term of patent 14 years

Int. Cl. D20—03

U.S. Cl. D96—12 R

Fig. 1

Fig. 2

Fig. 5

FIG. 1 is a left side elevation view of a mobile sign showing my new design;

FIG. 2 is a right side elevation view;

FIG. 3 is a front end elevation view;

FIG. 4 is a rear end elevation view; and

FIG. 5 is a top plan view.

The indicia are shown in broken lines in FIGS. 1 and 2 for illustrative purposes only.

I claim:

The ornamental design for a mobile sign, as shown and described.
